UNITED STATES PATENT OFFICE.

ALBERT R. HOLLER, OF ERIE, PENNSYLVANIA.

PISTOL-HOLDING DEVICE.

Application filed February 8, 1922. Serial No. 535,105.

To all whom it may concern:

Be it known that I, ALBERT R. HOLLER, a citizen of the United States, residing at Erie, in the county of Erie and State of Pennsylvania, have invented new and useful Improvements in Pistol-Holding Devices, of which the following is a specification.

This invention is designed to form a convenient mounting for a pistol and is of particular advantage in automobiles. In carrying out the invention in connection with automobiles a pocket is provided in the instrument board with a spring-actuated cover which when released projects the pistol into easy position to be grasped. Outside of the convenience of this location of the pistol the movement to the instrument board is not so apt to be resented as to any other part of the machine.

The invention is illustrated in the accompanying drawings as follows:—

Fig. 1 shows a central vertical section of the device.

Fig. 2 a plan view of the pistol clip.

Figs. 3 and 4 front and rear views of this clip.

Fig. 5 a rear view of the inwardly extending case.

Fig. 6 a front elevation of the plate for the instrument board.

Fig. 7 a section on the line 7—7 in Fig. 6.

Fig. 8 a view similar to Fig. 1 of an alternative construction.

Fig. 9 a front elevation of the plate showing the alternative construction.

Fig. 10 a vertical section of the catch for the cover in said structure.

1 marks the instrument board or dash, 2 a cover plate for an opening in the dash, 3 an opening in the cover plate, and 4 an inwardly extending case for housing the pistol, the case having the projecting ears 4^a which are secured to the cover plate by screws 4^b. A cover 5 is hinged on the cover plate at 6. It is provided with a latch strap

7 through which a latch 8 extends when moved to locking position. The latch 8 is carried by a pin 9 which extends through a slot 10 and a finger button 11 is arranged outside of the cover plate 2. It will readily be seen that if the cover plate is closed and the latch moved downwardly into the strap 7 the cover will be locked in a closed position until the latch is moved upwardly

55 out of the strap. The case 4 has inwardly extending walls

12 at its upper edge, these terminating a slight distance apart leaving an intervening slit 13. The ends of the tops are turned upwardly forming brackets 14 which support a guide rod 15, the guide rod having a head 16 at one end and a nut 17 at the other end for securing it in place. A pistol clip 18 which is made of spring metal with spring sides and of a shape to grasp the design of pistol that it is desired to carry is slidably mounted in the case 4. It has the upwardly extending ear 19 with a perforation 20 which is threaded on the rod 15. It also has an upturned ear 21 which extends through the slit 13 with a cross pin 22 which slidely secures the clip to the top wall of the case. A pistol 23 is shown in position in the clip 18. Normally this is pressed back against the cover 5 by means of a spring 24 which is coiled around the rod 15 and is compressed between the ears 14 at the front of the case and the upturned ear 19 on the pistol clip.

It will readily be seen that when the latch 80 releases the cover the spring acting on the pistol clip will move the pistol out through the opening 3 as the cover swings down into convenient position to be grasped by the operator. The clip 18 should grasp the 85 pistol sufficiently to prevent its removal when it is stopped against the end of the cover plate. A buffer spring 25 is preferably provided so as to save the shock.

In the alternative construction the latch 90 for the cover 26 is secured to the cover plate by a strap 27. A pull button 28 is carried by a pin 29 and the pin 29 is connected by a link 30 with the latch 26. It will readily be seen that as the pin 29 is withdrawn the 95 link 30 forces the latch upwardly, thus releasing the cover. In the structure the pistol clip 18 is of slightly different shape than the pistol clip in the preferred construction adapting it for a slightly different form of pistol 23^a.

What I claim as new is:—

1. The combination of a supporting wall having an opening therethrough; a cover for the opening; a pistol mounting; and means acting on the mounting to move a pistol through the opening as the cover is opened.

2. The combination of a supporting wall having an opening therethrough; a cover for the opening; a pistol mounting; and spring-actuated means acting on the mount-

ing to move a pistol through the opening as the cover is opened.

3. The combination of a supporting wall having an opening therethrough; a cover for the opening; a pistol mounting; a spring exerting pressure on the mounting which pressure is exerted against the cover; and a catch preferably over the dash for normally retaining the cover in a closed position.

10 4. The combination of a supporting wall having an opening therethrough; a cover for the opening; a pistol mounting; a guide on which the pistol mounting is slidingly mounted; a spring acting on the 15 mounting intending to move a pistol in the mounting outwardly through the opening; and a latch for the opening.

5. The combination of a supporting wall having an opening therethrough; a cover for 20 the opening; a pistol clip; a case extending inwardly from the opening; a guide rod on which the clip is slidingly mounted; and a spring acting against the clip.

6. The combination of a supporting wall 25 having an opening therethrough; a cover

for the opening; a case extending inwardly from the opening, said case having a slot through its top; a pistol clip; a guide rod above the slot; means extending from the clip through the slot; and a spring on the 30 rod acting against the clip.

7. The combination of a supporting wall; a housing for a pistol; a cover for the housing; and means for automatically moving the pistol to gripping position as the cover 35 is opened.

8. The combination of an automobile dash having an opening therethrough; a cover for the opening; a pistol mounting; and means acting on the mounting to move a 40 pistol through the opening as the cover is opened.

9. The combination of an automobile dash; a housing for a pistol; a cover for the housing; and means for automatically moving the pistol to gripping position as the 45 cover is opened.

In testimony whereof I have hereunto set my hand.

ALBERT R. HOLLER.
